UNITED STATES PATENT OFFICE

2,170,427

RADIATOR CONSTRUCTION

Frank C. Reynolds, New York, N. Y., assignor, by
mesne assignments, to American Radiator &
Standard Sanitary Corporation, New York,
N. Y., a corporation of Delaware

Application January 8, 1938, Serial No. 183,972

6 Claims. (Cl. 257—136)

My invention relates to improvements in heating apparatus, and the same has for its object to provide a radiator of the convector type which is simple in construction, efficient in operation, 5 and comparatively inexpensive to produce and assemble.

Further, said invention has for its object to provide a radiator enclosure consisting essentially of a base member upon which the heating 10 element is supported, and a top member cooperating with said base member for enclosing the heating element.

Further, said invention has for its object to provide a radiator enclosure consisting essentially of a base member having air inlet means therein and serving as a support for the heating element, and a housing separate from said base member and engageable therewith for enclosing said heating element and said support.

20 Further, said invention has for its object to provide a radiator enclosure in which the radiator supporting element and the base member of the enclosure, which contains the air intake opening, are formed as a unitary structure.

25 Further, said invention has for its object to provide a radiator enclosure composed essentially of a base member and a top member, and in which the base member, containing the air intake means, is engageable with the said top member and 30 serves to hold said top member duly positioned with regard to the said base member and the radiator supported upon the latter.

Further, said invention has for its object to provide a sheet metal enclosure for a radiator 35 consisting essentially of two parts, viz: a base member and a top member having air outlet openings, and in which the base member includes a frame structure forming a support or saddle for the heating element which is secured to the rear 40 of the base member forming the lower front portion of the enclosure and containing the air intake openings.

Other objects will in part be obvious and in part be pointed out hereinafter.

45 To the attainment of the aforesaid objects and ends my invention consists in the novel features of construction, and in the combination, connection and arrangement of parts hereinafter more fully described and then pointed out in the 50 claims.

In the accompanying drawings—

Figure 1 is a front view illustrating one form of radiator and enclosure constructed according to, and embodying my said invention;

55 Fig. 2 is a top view thereof;

Fig. 3 is a horizontal section on the line 3—3 of Fig. 1;

Fig. 4 is a vertical section on the line 4—4 of Fig. 1;

Fig. 5 is a front view of the radiator or heating 5 element with its support and air-intake member, the same being detached from the enclosure;

Fig. 6 is an end view of Fig. 5;

Fig. 7 is a perspective view of the support for the radiator or heating element and the attached 10 air intake member thereof;

Fig. 8 is a horizontal section on the line 8—8 of Fig. 1; and

Fig. 9 is an enlarged detail horizontal section 15 on the line 9—9 of Fig. 1.

In said drawings the radiator is shown as of the enclosed type, and comprises a heating element 10 composed of a plurality of sections 10^a communicatively connected at their upper and lower ends by the usual nipples indicated at Fig. 4, 20 and a sheet metal casing 11, comprising a back 12, top 13, and end portions 14.

The heating element is preferably constructed in the form of a panel, and each section of the panel provided with a rearwardly extending portion 10^b. 10^c and 10^d denote the supply and return pipes communicating with a source of heating medium, and 10^e a valve for controlling the supply of heating medium to said heating element. 30

The heating element is supported in elevated position upon a frame or saddle 15 with its front edge slightly overhanging the front of said support. The support is formed of sheet metal and includes a pair of transverse side members or plates 16 having laterally extending flanges 17, 18 at their upper and lower ends, respectively. The flanges 18 at the lower edge of the plates of members 16 are coextensive with the width thereof, and the upper flanges 17 extend rearwardly 40 beyond the rear edges of said plates or members and terminate in upwardly projecting ends 17^a. The said side members or plates are provided at their rear vertical edges with inwardly extending vertical flanges 16^a, which are coextensive in 45 height with said side members or plates. The said side members or plates are secured together at their rear edges by longitudinal angle members 19, 19^a which are spot-welded at their opposite ends to the inner sides of the vertical flanges 16^a adjacent the upper and lower ends thereof, and at the upper and lower ends of their forward edges said side members or plates are provided with inwardly-extending ears 20. 50

21 denotes a perforated front plate or grill, 55

which is secured at its central portion along its marginal portions to the ears 20 of the side members or plates 16 by spot-welding or other suitable means. The said perforated plate 21 is provided 5 at its opposite vertical edges with forwardly-extending flanges 22 coextensive in height with said plate 21, and along its upper edge said plate is provided with a narrow, rearwardly extending flange 23. The perforated bottom plate or grill 10 21, together with the attached supporting frame 15, form a support or saddle upon which the heating element 10 is mounted.

The enclosing casing 11 has its back members 12 formed of sheet metal and to the opposite 15 vertical edges thereof are secured the inturned vertical edges 25 of the end members 14 which are U-shape in cross-section and have their forward vertical edges 27 turned inward and terminate in rounded, rearwardly extending portions 20 28.

The top 13 is provided along its rear and front edges with depending flange portions 29, 29^a, respectively, and at its opposite short ends with 25 corresponding flanges 30. The lower edge 31 of the front flange 29^a is also rounded and directed rearwardly to correspond with the inwardly extending vertical edges 28 of the end members 14.

The top 13 has the edges of its several flanges 30 29, 29^a and 30 conformed to the corresponding upper edges of the back member 12, the end member wall 30, and the rearwardly extending portion 28 of said end member, and is secured in place by a strap 32 which is conformed to 35 the inner surfaces of said end member wall 30, the front flange 29^a, and its inwardly extending portion 28, and is secured thereto by spotwelds 33.

The upper edge of the back 12 is secured to the depending flange 29 of the top by screws 34.

40 The upper surface of the top 13 is provided with apertures 35 to form a grill, and below said top is movably supported a slide 36 having apertures 37 therein which may be brought into register with the apertures 35 in the top by movement of 45 said slide to permit of the escape of heated air from the casing.

The said slide 36 is supported upon longitudinal rails or guides 38 secured to the under side of the top, and is provided with a knob or finger portion 39 which extends through a slot 40 in said top 13 for operating said slide.

50 The end members 14 are provided upon their inner sides adjacent the lower ends of the rearwardly extending flanges 27 with ears or lugs 41 to receive therebetween the outwardly extending vertical flanges 22 of the perforated bottom plate 21 to hold the parts detachably secured together when the enclosure is adjusted into position over the heating element and its support.

60 A suitable aperture 42 is provided in the top 13 to accommodate the stem of the valve 10^e for controlling the supply of heating medium to the radiator.

65 It is to be noted that a feature of my invention is the constructing of the casing or enclosure of two essential parts, viz: the upper or enclosing portion and the base member which is embraced thereby, and which includes, as an integral part 70 thereof, the supporting means or saddle for the heating element.

75 Further, it is to be noted that since each of the two parts constituting the enclosure is a complete unit it merely becomes necessary to engage the one with the other to complete the enclosure,

and that no fastening devices of any kind are required to assemble the apparatus for use.

The operation of the apparatus will be obvious. It need merely be noted that the apparatus may be used either as a radiation and convection heating apparatus by opening the air outlets at the top of the casing, or as a radiation heating apparatus only by closing the air outlets in said top and relying upon the portion of the heating element exposed at the opening in the front of the casing.

Having thus described my said invention, what I claim and desire to secure by Letters Patent is:

1. An apparatus of the character described comprising a supporting frame including a front 15 wall member fixed thereon and having air inlet openings therein, a heating element mounted upon said support, and an enclosure for said heating element provided with air outlet openings and including end members; said front wall 20 member bridging the space between said end members below said heating element and detachably secured at its ends to said end members.

2. An apparatus of the character described comprising a supporting frame, a heating element mounted thereon, said supporting frame including longitudinal front and back members and transverse members connecting said longitudinal members, said longitudinal front member having air intake openings therein, and a casing 30 having air outlet openings and a cut-out front portion to expose the front of said heating element and interengaging at the lower edges of its cut-out portion with the ends of said longitudinal front member and forming therewith an enclosure 35 for said heating element.

3. An apparatus of the character described comprising a supporting frame including a front 40 wall member fixed thereon and having air inlet openings therein, a heating element mounted upon said support, and a casing provided with air outlets and including back, top and end members; said front wall member bridging the space between said end members below said heating element and detachably secured at its ends to 45 the end members of said casing.

4. An apparatus of the character described comprising a support including longitudinal front and back members, and transverse members connecting said longitudinal front and back members; said front member having air intake openings therein, a heating element mounted upon said support, a casing having air outlet openings and including back, top and end members and providing an opening at the front thereof intermediate said end members, said front member being disposed between the end members of said casing, and means on said end members for securing the ends of said front member in position thereon.

5. An apparatus of the character described comprising a support, a heating element mounted thereon, a casing including back, top and bottom members, said top member having air outlet openings, means for controlling said outlet openings; said casing providing an opening at the front thereof intermediate said end members, and said end members having rearwardly-extending inner vertical edges, and retaining means along said edges, a front plate separate 70 from said casing, fixed to said support, and disposed at the front of said casing between the end members thereof and provided with air intake openings communicating with the interior of said casing, and forwardly-extending flanges at 75

the opposite vertical edges of said front plate engaging with the retaining means on said end members.

6. An apparatus of the character described comprising a support therefor including longitudinal front and back members and transverse intermediate members connecting said longitudinal members; said longitudinal front member having air intake openings therein, a relatively flat heating element mounted upon said

support, and a casing including back, top and end members, said end members terminating at their front edges in inwardly and rearwardly directed vertical ends interengaging with the opposite ends of said longitudinal front member, and 5 providing an opening above said front member to expose the front of the heating element mounted on said support.

FRANK C. REYNOLDS. 10
